UNITED STATES PATENT OFFICE.

ELLSWORTH P. DE FRANCE, OF LAKESIDE, NEBRASKA.

BITLESS BRIDLE.

1,333,474.

Specification of Letters Patent. Patented Mar. 9, 1920.

Application filed October 10, 1919. Serial No. 329,860.

To all whom it may concern:

Be it known that I, ELLSWORTH P. DE FRANCE, a citizen of the United States, and resident of Lakeside, in the county of 5 Sheridan and State of Nebraska, have invented a certain new and useful Improvement in Bitless Bridles, of which the following is a complete specification.

The present invention pertains to harness 10 and aims to provide an improved bridle of the bitless type, which will be of a humane character, while retaining all the properties of checking or restraining the animal.

To this end I have devised a bridle comprising a headstall with nose band and check member slidingly engaging the band and operated to compress the latter tightly about the nostrils of the animal.

It is also sought to provide an improved, 20 article of this character, including a nose band of loop form and throat latch adjustably connected thereto and adapted to be conveniently fitted to take up all the slack in said nose band.

25 The nature of the invention will now be described by reference to the accompanying drawing illustrating one form of construction, after which the novel features will be set forth in the appended claims.

30 In the drawing—

Figure 1 is a perspective view illustrating the improved bridle in its position for use;

Fig. 2 is a side view of the same, illustrating the lower portion of the bridle; and

35 Fig. 3 is a plan view of the nose band, with the check members fitted thereon.

Referring to the drawing in detail, this shows the bridle as comprising a headstall, composed of a browband 5, and cheek straps 40 6, carrying loops 7 at their lower end, said loops being connected by a nosestrap 8. The lower forked ends of the band 5 are provided with loops 9, which support the front of a nose band 10, adapted to be supported 45 low over the nostrils of the animal, as illustrated in Figs. 1 and 2, the side portions of said band being slidingly accommodated within sleeves 12, formed in check members or levers 13, which are pivotally supported 50 by the loops 7. The check levers 13 are of suitable length and adapted for the attachment of checkrein 14. The bridle further

comprises a rope 15, which is suitably noosed to form a throat latch passed slidingly through the loop at the upper end 55 of the browband 5. The nose band 10 is formed with a knot 16 at its rear end, where the rope 15 is looped about said band a sufficient number of times to effect a reasonably snug fit of the noseband when in position 60 for use.

With the construction shown and applied as described, it is apparent that an effective bridle structure is provided in which the check members normally merely slide upon 65 the side portions of the nose band, but when a restraining force is required, the swinging of the check members upon their pivots by pulling on the rein 14, crimps the noseband and obviously compresses the animal's nostrils in such a manner as to effectually curb 70 any unruly tendency. Under all normal circumstances the bridle is comfortable and humane to the animal, while sacrificing none of the essential requirements of a bridle. 75 The article is furthermore conveniently adjustable to fit the animal by virtue of the peculiar form of the noseband having the knot at the rear end to which the throat latch is adjustably attached.

While I have shown and described what I now regard as the preferred form of construction, I desire to reserve the right to make such changes as may fairly fall within the scope of the appended claims.

What I claim is:

1. A bitless bridle comprising a head stall, a throat latch and nose band supported from said head stall, and check levers carried by the head stall and formed 90 with sleeve portions slidingly engaging the side portions of said nose band.

2. A bitless bridle comprising a headstall, a throat latch and nose band supported from said head stall, said nose band having 95 a knotted rear end portion receiving said throat latch in adjustably looped relation for taking up the slack in said nose band, and check levers carried by the head stall and formed with sleeve portions slidingly 100 engaging the side portions of said nose band.

In witness whereof I affix my signature.

ELLSWORTH P. DE FRANCE.
